CONTROL UNIT FOR A BURGLAR ALARM SYSTEM

Harry D. Dwyer, 1601 Poplar St., Anderson, Ind. 46012;
Betty M. Dwyer, administratrix of said Harry D. Dwyer,
deceased

Filed Nov. 29, 1965, Ser. No. 88,251

Term of patent 14 years

(Cl. D72—1)

Fig. 1.

Fig. 2.

FIG. 1 is a perspective view taken from the front, top, and one side of a control unit for a burglar alarm system showing my new design; and

FIG. 2 is a perspective view taken from the rear, bottom, and side opposite that shown in FIG. 1.

The dominant features of my design reside in the portions shown in full lines, said design being characterized by the appearance of the recessed front panel and the arrangement of the control elements thereon as illustrated in FIG. 1.

I claim:

The ornamental design for a control unit for a burglar alarm system, as shown and described.
